UNITED STATES PATENT OFFICE.

WILLIAM E. LEWIS, OF CORRY, PENNSYLVANIA.

THERMOSTAT.

SPECIFICATION forming part of Letters Patent No. 398,740, dated February 26, 1889.

Application filed February 23, 1888. Serial No. 265,025. (No model.)

To all whom it may concern:

Be it known that I, WILLIAM E. LEWIS, a citizen of the United States, residing at Corry, in the county of Erie and State of Pennsylvania, have invented a new and useful Thermostat, of which the following is a specification.

This invention has relation to improvements in apparatus whereby the temperature of an apartment may be maintained at a uniformly-determined degree by the automatic regulation of the supply of the heating medium.

The invention will be fully understood from the following description and claims, when taken in connection with the accompanying drawing, in which the figure is a vertical longitudinal sectional view of a thermostat embodying my improvements.

Referring by letter to the said drawing, B indicates a metallic reservoir, which is here shown as of a cylindrical form, and which is designed to be filled with any suitable liquid having a high degree of expansibility. This reservoir is closed at its upper end by a cap, A, designed to fit tightly therein, so as to form an air-tight joint with the said reservoir. This cap A is provided with a filling-aperture, C, and which is closed by a screw-plug, D. The cap is furthermore provided with an outlet-aperture, E, which extends through a lateral horizontal branch, as shown at H', which branch is externally threaded, as shown, to receive a union, F, whereby a connection is had with one end of a pipe, Z, a packing, G, being interposed at the union before mentioned. The lower end of the reservoir has firmly fixed to it a plate, H, which is recessed annularly, as shown at J, and in this recessed portion of the said plate is secured a diaphragm, N, preferably of metal. This plate is also provided with screw-holes in its margin for the attachment of the bottom plate, I, which has similar apertures to receive the connecting-screws K. This bottom plate, I, has a centrally-distended hollow portion, P, for the reception of a headed nut, M, which nut is secured to the under side of the diaphragm N, and is designed to move with it.

S indicates a regulating-screw, which is provided for the greater portion of its length with right-hand threads, R, and its upper end is reduced, as shown at o, where it is provided

with left-hand threads, or threads which run in an opposite direction to the right-hand threads. This screw is seated in a screw-tapped aperture in the lower end of the bottom plate, I, and its upper reversely-threaded portion engages threads in the nut M. By turning the screw to the right the diaphragm N will be forced outwardly, slightly increasing the size of the reservoir B and diminishing the pressure of the liquid therein, while by turning the said screw to the left the diaphragm will be pushed inwardly, which will cause a pressure, and by means of which the apparatus can be set for different degrees of heat.

T indicates a valve-chamber having inlet and outlet ports of the usual form, which ports are internally threaded to receive connecting-pipes for the delivery of gas or other combustible fluid.

Screwed in the breast of the valve case or frame is a plate, D², having a chamber therein to receive a spiral spring, which surrounds the valve-stem, as shown, and presses against a head on the said stem, so as to normally keep the fuel-passage open. This plate D² is provided with threaded apertures in its margin to receive fastening-screws, which pass through an upper plate, D'. This plate D' is recessed in its under side, and in the recess is secured a diaphragm, D⁴, which is designed to be held normally raised by the action of the spring surrounding the valve-stem. This plate D' is also provided with a central inlet-aperture, D⁵, around which are formed external threads to receive a packing-gland, C', which latter also serves as a means of uniting the said plate with the lower end of the tube Z.

Instead of using liquid in the reservoir air may be used.

In operation, after the parts have been properly connected, the screw-plug D is removed until the reservoir has been filled with liquid up to within about one inch of the top. The plug D is then screwed down, and the apparatus is ready for use, and the valve held lifted by the action of the spring, so as to allow the gas to flow for heating purposes. When the liquid has become sufficiently warm or hot and begins to expand, it will pass out of the reservoir through the opening E, and thence down the pipe Z upon the diaphragm beneath the same, thereby seating the valve

and checking the flow of gas, the diaphragm of the main reservoir being regulated by means of the right-and-left-threaded rod S.

Having described my invention, what I claim is—

1. In a thermostat, the combination, with a reservoir constructed as described and provided with the diaphragm at its lower end, of the threaded nut beneath the diaphragm and the right-and-left-threaded regulating-screw tapped in the bottom of the said reservoir and engaging the said nut, substantially as specified.
2. The combination, with a reservoir constructed as described, of the cap in the upper end of the said reservoir having a filling-aperture and the lateral branch provided with an

outlet-aperture, the pipe Z, connected to the said branch, and the valve-regulating device secured to the lower end of the said pipe, substantially as specified.

3. In a thermostat, the combination, with the reservoir having the diaphragm at its lower end, threaded nut below the diaphragm, and the right-and-left-threaded regulating-screw, of the cap having the inlet and outlet aperture, the valve-regulating device, and the pipe Z, connecting the said valve-regulating device with the outlet-aperture of the reservoir, substantially as specified.

WILLIAM E. LEWIS.
